KNITTING NEEDLE

Hazel E. Stallman, Pontiac, Mich.

Application April 3, 1939, Serial No. 265,803

4 Claims. (Cl. 66—117)

This invention relates to knitting needles and more particularly to an improved head for a knitting needle.

An object of this invention is to provide an improved knitting needle head which may be secured on one end of a knitting needle, the head embodying means whereby the user of the needle may be able to keep count of the various steps taken during the knitting of an article.

10 Another object of this invention is to provide an improved knitting needle head having associated therewith a counter or calculator which will assist in the knitting of an article as it will permit the user of the needle to more readily 15 keep track of the various steps being taken in the knitting operation without the use of a pencil and paper as is at present the case.

A further object of this invention is to provide a knitting needle and head which includes a 20 revolable cap provided with a window for exposing numerals or other indicia carried by the head.

A still further object of this invention is to provide a knitting needle head which is not only 25 provided with means to facilitate counting of steps taken in the knitting operation, but also provided with differentiating indicia so that where two knitting needles are used, as is the usual case, the steps taken in the use of one needle 30 may be more readily determined.

To the foregoing objects and to others which may hereinafter appear, the invention consists of the novel construction, combination and arrangement of parts as will be more specifically 35 referred to and illustrated in the accompanying drawing, wherein is shown an embodiment of the invention, but it is to be understood that changes, variations and modifications may be resorted to which fall within the scope of the 40 invention as claimed.

In the drawing:

Figure 1 is a detail side elevation of a knitting needle having a head mounted thereon constructed according to an embodiment of this invention.

45 Figure 2 is a fragmentary sectional view taken on the line 2—2 of Figure 1.

Figure 3 is a plan view of the knitting needle head.

50 Figure 4 is a plan view of the inner portion of the head carrying the numerals or other indicia, and

Figure 5 is a fragmentary side elevation of the device.

55 Referring to the drawing, the numeral 10 design-

nates generally a knitting needle provided with a substantially blunt point 13 at one end thereof.

The needle 10 at the opposite end is provided with a head generally designated as 11 and which comprises a body 12 provided with a socket 14 in which the adjacent end of the needle 10 is adapted to be adhesively secured. The body 12 in the present instance is substantially cylindrical in transverse section and at its outer end merges into and axially of the inner face of a disc-like member 15 constituting a carrier having a diameter substantially greater than the diameter of the body. The member 15 is formed of an outer portion of uniform diameter and an inner portion 16 which gradually decreases in diameter from the said outer portion to the outer end of body 12. The outer face 17 of member 15 is of substantially conical or tapered configuration, and is provided with a circular row of spaced aligned numerals 18 disposed in close proximity to the edge of the outer portion of said member or carrier 15.

Rotatably mounted on and connected to the member 15 is a cap generally indicated at 19 and formed of a circular part 20 of substantially 25 conical contour bearing against and conforming in contour to the outer face of member 15, an annular flange 21 encompassing the outer portion of the member 15, and a frusto-conical shaped flange 22 carried by flange 21 and frictionally 30 engaging with the portion 16 of the body 12. The cap 19 in its part 20 and in proximity to its flange 21 is provided with an opening or window 23 for selectively exposing the numerals or indicia 18. The part or top 20 of cap 19 is also provided with 35 a character 24 which is adapted to differentiate one needle from the other so that the user of these needles can readily determine from the numerals exposed through the window 23 what steps in the form of stitches or groups of stitches 40 have been made with a particular needle. The periphery of the cylindrical flange 21 is adapted to be knurled or otherwise roughened so as to facilitate rotation of the cap 19 on the member 45 or carrier 15.

In the use of this device, the knitting needle 10 is adapted to be inserted in the socket 14 and securely fastened by an adhesive or other securing means. The head 11 may be formed out of substantially light weight material and the cap 19 50 may be rotatably secured on the flange 15 by crimping the inner portion 22 of the cap on the rear side of the portion 16 of member 15. This crimped portion 22 is adapted to frictionally hold the cap 19 against rotation on the member 55

15 so that the cap 19 will normally stay in its set position and permit normal use of the needle 10 without affecting the position of the cap 19. This device may be constructed at a small cost 5 and if desired, may be constructed as a new article of manufacture for mounting on a conventional needle wherein the usual head formed integral with the needle is cut off so that the outer end of the needle may be secured by suitable fastening means in the form of an adhesive 10 or the like in the socket forming part of the attachment.

What I claim is:

1. A knitting needle head comprising a disc-like carrier having an outer portion of uniform diameter and an inner portion gradually decreasing in diameter throughout inwardly from said outer portion, a socket forming means for mounting on and for securing to one end of the 20 needle, said means being integral with said inner portion, said carrier being provided on a part thereof with spaced selectively exposable indicia, and a rotatable cap mounted on the carrier and being formed with a part coacting with the said 25 inner portion for connecting the carrier and cap together and for frictionally securing the cap, said cap including another part formed with a window for selectively exposing said indicia.
2. A knitting needle head comprising a disc-like carrier having an outer portion of uniform 30 diameter and an inner portion gradually decreasing in diameter throughout inwardly from said outer portion, a socket forming means for mounting on and for securing to one end of the needle, said means being integral with said inner portion, said carrier being provided on a part thereof with spaced selectively exposable indicia, a rotatable cap mounted on the carrier and being formed with a part coacting with the said 35 inner portion for connecting the carrier and cap together and for frictionally securing the cap, said cap including another part formed with a window for selectively exposing said indicia, that part 40 of the carrier provided with said indicia being of conical contour, and that part of the cap provided 45 with the window corresponding in contour to and disposed in superimposed relation with respect to that part of the carrier provided with the indicia, and that part of the cap provided with the window being formed on its outer face with a needle designator.

vided with the window corresponding in contour to and disposed in superimposed relation with respect to that part of the carrier provided with the indicia.

3. A knitting needle head comprising a disc-like carrier having an outer portion of uniform 5 diameter and an inner portion gradually decreasing in diameter throughout inwardly from said outer portion, a socket forming means for mounting on and for securing to one end of the 10 needle, said means being integral with said inner portion, said carrier being provided on a part thereof with spaced selectively exposable indicia, a rotatable cap mounted on the carrier and being formed with a part coacting with the said 15 inner portion for connecting the carrier and cap together and for frictionally securing the cap, said cap including another part formed with a window for selectively exposing said indicia, and that part 20 of the cap provided with the window being formed on its outer face with a needle designator.

4. A knitting needle head comprising a disc-like carrier having an outer portion of uniform 25 diameter and an inner portion gradually decreasing in diameter throughout inwardly from said outer portion, a socket forming means for mounting on and for securing to one end of the needle, said means being integral with said inner portion, said carrier being provided on a part thereof with spaced selectively exposable indicia, a rotatable cap mounted on the carrier and being formed with a part coacting with the said 30 inner portion for connecting the carrier and cap together and for frictionally securing the cap, said cap including another part formed with a window 35 for selectively exposing said indicia, that part of the carrier provided with said indicia being of conical contour, that part of the cap provided with the window corresponding in contour to and disposed in superimposed relation with respect to that part of the carrier provided with the indicia, and that part of the cap provided with the window being formed on its outer face with a needle designator.
